INVENTOR

BY *Walter Grumbacher*
William S. Gluck
ATTORNEY

UNITED STATES PATENT OFFICE.

WALTER GRUMBACHER, OF NEW YORK, N. Y.

BRUSH.

Application filed August 17, 1923. Serial No. 657,916.

To all whom it may concern:

Be it known that I, WALTER GRUMBACHER, a citizen of the United States, and a resident of the city, county, and State of New York, 5 have invented certain new and useful Improvements in Brushes, of which the following is a full, clear, and exact specification.

My present invention relates generally to 10 brushes and more particularly to an arrangement for holding bristles within a holder.

While as will be observed, I have disclosed 15 my invention herein as applied to a brush in which the handle member is a quill within one end of which the bristles are received and held because it is in this specific association that my invention was first evolved, nevertheless it will be understood that my invention possesses utility in brushes other than of the specific character in connection 20 with which this invention is herein disclosed.

Among the more important objects of my invention is the provision of a brush which while simple in construction and economical in cost is nevertheless efficient in operation 25 and unobjectionable in use.

For the attainment of these objects and 30 of such other objects as will appear or be pointed out hereinafter, I have illustrated one embodiment of my invention in the drawings wherein:

Figure 1 is a view in side elevation of the brush; and

Figure 2 is a longitudinal section taken on line 2—2 of Figure 1.

Upon viewing the figures of the drawing 35 it will be observed that I have herein illustrated a brush which comprises the bristles 10, and the handle member 11. This handle member 11 is preferably in the form of a quill within the end 12 of which the bristles 40 are received. The bristles, as will be observed, are inserted into the end 12 of the quill 11 for a substantial distance. For securing these bristles in position in the quill, 45 I employ a wire 14 which is wound about the quill 11 at a point 13 which is substantially intermediate the ends of that length of the bristles which is received within the end 12 of the quill 11.

The wire 14 is preferably wound about the 50 quill more than once, for reasons that will be obvious; for instance in the drawing, I show the wire as wound thereabout twice. The wire is preferably drawn tight about 55 the quill 11 in fact so tight as to compress and narrow the quill at the point 13 and

therefore to correspondingly compress the bundle of bristles within the quill 11. The ends 15 of wire are preferably then twisted as shown in 16 thereby keeping the wire ends 60 from separating and the wire from loosening. These twisted ends are then bent parallel to the longitudinal axis of the quill as shown in the drawings.

Upon viewing the figures of the drawing 65 it will be observed that I preferably turn this end 16 downward, i. e. toward the bristle end of the brush and into parallelism therewith and then force this end within the outlines of the brush as shown at 17 all 70 for reasons that I will now point out.

As is well known a brush of this type 75 is generally cleaned or wiped by moving a cloth or a similar article into contact with and along the brush in the general direction of the bristle end. By turning the end 16 downward i. e. toward the bristle and the brush, as already described, I therefore attain one of the important objects of my invention which is that the ends 15, 15 80 being bent in the general direction of the movement of the wiping element will not catch into the wiping material or in any other way interfere with the movement or use of the wiping action.

Additionally by forcing this end 16 within 85 the outlines of the brush, the bristles are further compressed thereby. In fact, this end 16 acts somewhat as a wedge increasing in size in the direction of the 90 bristle end and thus serving to hold the bristles against falling out of the brush.

Having thus described my invention and 95 illustrated its use what I claim as new and desire to secure by Letters Patent is the following:

1. In a device of the character described, a compressible tubular handle member, bristles positioned therein and a bendable member wound tightly about said tubular 100 member to compress it so as to produce an interengagement between the handle member and the bristles, the free ends of the bendable member being interengaged and twisted and then bent longitudinally 105 of the handle member and in the direction of the bristles.

2. In a device of the character described, a compressible tubular handle member, bristles positioned therein and a bendable 110 member wound tightly about said tubular member to compress it so as to produce

an interengagement between the handle member and the bristles, the free ends of the bendable member being bent longitudinally of the handle member and in the direction of the bristles.

3. In a device of the character described, a compressible tubular handle member, bristles positioned therein and a bendable member wound tightly about said tubular member to compress it so as to produce an interengagement between the handle member and the bristles, the free ends of the bendable member being interengaged and bent longitudinally of the handle member and in the direction of the bristles.

4. In a device of the character described, a compressible tubular handle member, bristles positioned therein and a bendable member wound tightly about said tubular member to compress it so as to produce an interengagement between the handle member and the bristles, the free ends of the bendable member being bent longitudinally of the handle member and in the

direction of the bristles, said free ends being forced into angular engagement with the handle member so as to cause a wedging engagement between the bristles and the handle member.

5. In a device of the character described, a compressible tubular handle member, bristles positioned therein and a bendable member wound tightly about said tubular member to compress it so as to produce an interengagement between the handle member and the bristles, the free ends of the bendable member being interengaged and twisted and then bent longitudinally of the handle member and in the direction of the bristles, said free ends being forced into angular engagement with the handle member so as to cause a wedging engagement between the bristles and the handle member.

In testimony whereof, I have hereunto signed my name.

WALTER GRUMBACHER.
